J. H. OSBORN,
WEATHER STRIP,
APPLICATION FILED JAN. 19, 1920.

1,397,979.

Patented Nov. 22, 1921.

UNITED STATES PATENT OFFICE.

JAMES H. OSBORN, OF MOUNT VERNON, ILLINOIS.

WEATHER-STRIP.

1,397,979.

Specification of Letters Patent.

Patented Nov. 22, 1921.

Application filed January 19, 1920. Serial No. 352,280.

To all whom it may concern:

Be it known that I, JAMES H. OSBORN, a citizen of the United States, residing at Mount Vernon, in the county of Jefferson and State of Illinois, have invented a new and useful Weather-Strip, of which the following is a specification.

The device forming the subject matter of this application is a weather strip, and the invention aims to provide novel means whereby when a door is swung to an open position, a closure member will be elevated.

Another object of the invention is to provide novel means for hingedly connecting the closure member with the door.

A further object of the invention is so to construct the closure member that the same will be held in place securely but hingedly upon the carrier, the ends of the groove in the door, wherein a portion of the carrier is mounted, being closed by the said member.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:—

Figure 1 is a vertical section taken through a door equipped with the device forming the subject matter of this application, the door jamb appearing in elevation, and the door being closed; Fig. 2 is a view similar to Fig. 1, the door being open; Fig. 3 is a horizontal section taken approximately on the line 3—3 of Fig. 1; Fig. 4 is a perspective view showing the closure member and the carrier, one of the wings of the closure member being bent out of normal position, and Fig. 5 is a section taken approximately on the line 5—5 of Fig. 2.

The numeral 1 marks a door frame including a base 2 and a jamb 3, the jamb 3 carrying a stop strip 4. A door 5 is united by hinges 6 to the jamb 3 and cooperates with the stop strip 4. A lifting block 7 fits

against the jamb 3 and is held on the base 2 by a securing element 8, the lifting block 7 having an inclined surface 9.

The invention includes a carrier 10, preferably in the form of a plate, bent intermediate its longitudinal edges to form an upstanding trough-shaped receiver 11. The plate or carrier 10 is back bent upon itself at the point of juncture between one wall of the receiver 11 and one side portion of the carrier, to form a lip 12 extended inwardly with respect to the receiver. The carrier or plate 10 may be provided with openings 14. The device includes a closure 15 preferably in the form of a plate, provided at its ends with bendable wings 16. Along one of its longitudinal edges, between the wings 16, the closure 15 is bent to form a curved flange 17 located in the receiver 11 and coöperating hingedly with the lip 12 of the carrier 10. A groove 18 is formed in the lower edge of the door 5, the receiver 11 being located within the groove 18, and the plate or carrier 10 being secured to the lower edge of the door 5 by attaching elements (not shown) extended through the openings 14.

In practical operation one of the wings 16 may be bent outwardly into alignment with the closure 15 as shown at the right hand end of Fig. 4. The flange 17 of the member 15 may then be slid into the receiver 11, to form a hinged connection between the member 15 and the lip 12 of the part 10. The wing shown at the lower right hand end of Fig. 4 may then be bent at right angles to the part 15 and the wings 16 thus serve to prevent the flange 17 from sliding endwise out of the receiver 11.

When the door is swung to an open position, the depending closure 15 will ride along the inclined surface 9 of the lifting block 7 and thus be raised, as indicated in Fig. 2. When the door is swung to a closed position, the part 15 will ride downwardly along the inclined surface 9 of the block 7 and coöperate with the base 2, as indicated in Fig. 1, the construction, obviously, being such that a draft of air beneath the lower edge of the door 5 will be prevented. It is to be observed that the wings 16 serve not only to retain the closure 15 pivotally or hingedly connected with the member 10, but, at the same time, the wings constitute clo-

sures for the ends of the groove 18 in the lower edge of the door and give a finished appearance to the structure.

Having thus described the invention,
what is claimed is:—

In a device of the class described, a carrier plate provided with a trough-shaped receiver portion, the plate being bent upon itself at one of the edges of said receiver portion to form a double-walled lip extended inwardly from said edge of the receiver portion; and a closure having a hook-shaped flange located in said receiver portion and extended about the lip to form a hinged con-

nection between the closure and the receiver portion, the closure having bendable end wings located at right angles to the flange and coöperating with the receiver portion to limit endwise movement of the closure and to maintain the closure hingedly mounted on the receiver portion.

In testimony that I claim the foregoing as my own, I have hereto affixed my signature in the presence of two witnesses.

JAMES H. OSBORN.
